UNITED STATES PATENT OFFICE.

GEORGE W. CANNON, OF POUGHKEEPSIE, NEW YORK.

DUMB-WAITER.

SPECIFICATION forming part of Letters Patent No. 361,263, dated April 19, 1887.

Application filed February 17, 1887. Serial No. 227,985. (No model.)

To all whom it may concern:

Be it known that I, GEORGE W. CANNON, a citizen of the United States, residing at Poughkeepsie, county of Dutchess, and State of New York, have invented a new and useful Dumb-Waiter, of which the following is a specification.

My invention relates to improvements in dumb-waiters; and it consists of a combination and an arrangement of pulleys, rope, and dumb-waiter car and counterpoise-weight, so arranged as to dispense entirely with the usual hoist-wheel and axle, and use only three sizes of pulleys and one continuous rope for operating the same. I can put upon the car another rope, connecting it with the counterpoise-weight, which is used simply as a safety appliance, which may or may not be used, at the option of the parties.

The novelty of my invention consists in the simplicity of construction and ease of operation. By the use of one continuous rope its slack is always taken up, and it is easily operated. My pulleys may all be made of the same size; but for ease of operation I prefer to place upon the upper shelf three sizes, in order to lessen friction and carry the ropes to their respective positions with the least possible friction.

I will now explain my invention with reference to the drawings.

Figure 1 is a plan view of my dumb-waiter. Fig. 2 is a sectional view, looking down upon the same, showing the counterpoise-well at one corner thereof. This well may be placed in any position around the car-well which convenience of construction may dictate, and the pulleys on this shelf may be changed accordingly.

Like letters indicate like parts.

A shows the large pulley-wheel, which takes the rope from the front corner of the car-well, and carries it at any angle desired to a point vertically over one side of the pulley or pulleys on the top of the waiter-car.

B shows a pulley, taking the rope at the other front corner of the car-well and carrying it in any desired direction to the pulley located over the counterpoise-well.

C shows the pulley that conducts the rope 50 perpendicularly downward into the weight-well, to and around the movable pulley E.

E shows the movable pulley which sustains the counterpoise-weight, and to the top of which the safety-rope L, when used, may be 55 attached.

F shows the pulley attached to the top of the car, near the middle point thereof; and in case of large dumb-waiters two pulleys of this description may be placed on top of the car and 60 the hoist-rope passed under both of them.

G shows the car of the dumb-waiter.

H shows the continuous working-rope, one end of which is attached to the bottom of the upper shelf, K, at I, and passes vertically 65 down under the pulley F and over the pulley A, and down the front side of the car-well under the pulleys P and O, and up the other front edge of the car-well over the pulleys B and C, and down under the movable pulley E 70 and up to the bottom of the shelf K at the point J, where this end of the rope is fastened.

K shows the upper shelf above the car and counterpoise-well.

L shows the safety-rope, attached at one end 75 near the pulley F to the car, and at the other end, after passing over the pulley D, it is made fast to the movable pulley E.

M shows the counterpoise-weight.

It may be seen by my construction that the 80 counterpoise or weight well may be located on either of the three sides of the car-well, as convenience of construction may dictate, and this well may be inclosed in such manner that the block E will not revolve by any untwisting of 85 the rope. The holes through the shelves above and below the car-well, through which the ropes work, are provided with iron thimbles.

Having thus described my invention, what 90 I claim is—

1. The combination of a dumb-waiter car having connected thereto a counterbalance-weight, M, with the pulleys A B C F, and pulley-block E, arranged, as shown, upon and beneath 95 the shelf K, and the operating-rope H, secured to the shelf at I and passing under the pulley F, over the pulley A, and under the pulleys P

and O, and over the pulleys B and C, and under the movable block E, and secured to the shelf K at J, as shown and described.

2. The combination of a dumb-waiter car, having connected therewith a counterbalance-weight M, the pulleys A B C F, and pulley-block E, arranged, as shown, upon and beneath the shelf K, the operating-rope H, secured to the shelf at I and passing under the pulley F,

over the pulley A, and under the pulleys P and O, and over the pulleys B and C, and under the movable block E, and secured to the shelf K at J, the safety-rope L, and the pulley D, substantially as shown and described.

GEORGE W. CANNON.
